UNITED STATES PATENT OFFICE.

ABRAM E. FALOR, OF AKRON, OHIO, ASSIGNOR TO THE B. F. GOODRICH COMPANY, OF NEW YORK, N. Y., A CORPORATION OF NEW YORK.

TUBE-SKIVING APPARATUS.

Application filed May 19, 1924. Serial No. 714,415.

This invention relates to tube skiving machines, particularly to a machine for skiving the ends of a length of tubular stock preparatory to the splicing of the ends to form a hollow annular tubular body, such for example as an inner tube for a pneumatic tire, and it has for an object to provide an apparatus of this character which shall hold the tube end firmly during the cutting operation and thus effect a more accurate skiving which may be made nearer the tube end than heretofore has been possible.

The accompanying drawings illustrate the invention.

15 Fig. 1 is a view in elevation of a machine embodying a preferred form of my invention;

Fig. 2 is a view in longitudinal section through the operative parts of the machine;

20 Fig. 3 is a view in section through the suction valve of the machine; and

Fig. 4 illustrates a tube the end of which has been skived or beveled by means of my improved machine.

25 My invention in substance involves a suction means for holding securely the end of a thin rubber tube in a turned-back or cuffed condition on a mandrel which is movable into operative cutting position with respect

30 to a rotating, tubular knife for skiving of the end thereof to better adapt the tube end for splicing, and in the specific form illustrated comprises a hollow frusto-conical member or nozzle having a foraminous outer

35 wall portion upon which the tube is folded back and an enlarged portion forming a shoulder with the foraminous portion against which shoulder the tube end is placed prior to the skiving operation. The perforations

40 of the foraminous wall communicate with a chamber formed within the hollow frusto-conical nozzle and a valve-controlled conduit connected with a suction line serves to evacuate the chamber when the nozzle is moved

45 into operative-skiving position and to break the vacuum when the nozzle is retracted therefrom. In prior constructions, it has been the practice to make the mandrel on which the tube end is folded back much

50 larger than the tube being beveled and to stretch the tube end over the mandrel relying upon the elasticity of the tube to hold it thereon during skiving. In such constructions there is a considerable slippage of the

55 tube about the mandrel which causes ob-

jectionable irregularities in the bevel. In attempts to minimize this slippage, the beveled cut is made at a considerable distance from the tube end, thus wasting a considerable amount of material. The present 60 apparatus firmly holds the material being cut or beveled by vacuum pressure from within and thus permits the cutting operation to be performed at the very end of the tube with a great saving of material and 65 with the production of a clean, uniform bevel. Further, the nozzle being of substantially the size of the tubing, the tubing is readily slipped on and off the nozzle saving much time and labor in this operation.

70 Referring to the drawings, I show my tube skiving machine mounted upon a table 10 having a pedestal support 11. The machine consists essentially of a rotating knife 12, a motor 13 operatively connected thereto as 75 by shaft 14, and a mandrel 15 movable in the direction of the axis of rotation of the knife, all being of conventional construction in machines of this character.

75 The mandrel 15 comprises a bracket member 16 slidably supported on table 10 and a nozzle member 17. The nozzle 17 includes a frusto-conical nose portion 18 and a cylindrical shank portion 19, the latter secured in the bracket 16, and is provided with an axial 80 opening 20 for the reception of the tube 21 to be skived. A shoulder 22 rises abruptly 85 from the nose 18 to the shank 19 and serves for the positioning of the tube 21, as hereinafter described.

90 The annular wall of the mandrel 15 is constructed to provide therein an annular chamber 25 coextensive with the axial length of the nose 18 and which may extend through the shank 19 if desired. The outer 95 wall of the nose 18 is provided with a plurality of apertures 26, communicating with the chamber 25 and so spaced as to make the outer wall foraminous in character, as illustrated in Fig. 1.

100 The mandrel 15 has formed in the base of the bracket 16 a downwardly presented rack 28 which engages with a pinion 29 mounted on an axle 30 and adapted to be actuated by a crank arm 31. A valve 33 is disposed in alignment with the axle 30 and the ported 105 passages 34, 35 thereof may be formed in an extension of the axle 30, if desired. The valve 33 is provided with a port 37 from which a conduit 38 leads to a region of low 110

or vacuous pressure, as for example a vacuum pump, a port 39 connecting with the chamber 25 of the mandrel 15 by means of a flexible conduit 40, and a port 41 leading directly to the atmosphere. The setting of the pinion 29, shaft 30, and valve 33 is such that when the crank arm is moved to advance the mandrel 15 toward the knife 12 the port 41 is closed and then the port 10 37 opened to place the chamber 25 in communication with the suction line 38, and conversely at the completion of the retracted position of the mandrel 15, the port 37 to the suction line is closed and the chamber 15 25 then placed in communication with the atmosphere through port 41. A vacuum pressure is thus maintained in chamber 25 for holding the tube end firmly to the nose 18 during the skiving action and immediately 20 before and after this action. The vacuum is automatically broken, however, at the outermost position of the mandrel 15, so that the positioning and removing of the tube may be readily accomplished.

25 The operation of the above described machine is briefly as follows: With the mandrel in the outer retracted position shown in Fig. 1, one end of a rubber tire is inserted through the opening 20 of the mandrel 15 and folded back over the outer wall of the nose 18, the margin of the tube end abutting the shoulder 22. The crank arm is then pulled back to advance the mandrel 15 and tube carried thereby into operative position 30 with respect to the rotating knife 12. Upon the first advancing movements of the mandrel, the chamber 25 is connected to the suction line 38 through the valve 33 and the vacuum created therein causes the cuffed portion of the tube end to be pressed firmly to the outer wall of the nose 18. The vacuum in chamber 25 is maintained during the skiving operation and is broken only when the mandrel has again been withdrawn to its 35 outer retracted position. The tube with its end properly beveled is then readily removed from the mandrel, and the machine is ready for a succeeding operation.

Modifications may be resorted to within 40 the scope of this invention and I do not wholly limit my claims to the specific construction shown.

I claim:

1. In a tube skiving machine, in combination, an annular member provided with a frusto-conical portion adapted to support a tube end, said frusto-conical portion being hollow to form a vacuum chamber and being further provided with passage ways leading 55 from the vacuum chamber through its outer wall, and means for making and breaking a vacuum within the vacuum chamber.

2. In a tube skiving machine, in combination, a hollow nozzle externally tapered at 60 one end and through which the end of a tube

adapted to be passed and to be folded back over the externally tapered portion, said hollow nozzle being provided with passage ways leading from the interior thereof to the outer wall of said tapered portion, a 70 rotating knife adapted to circumscribe said folded-back portion of the tube and to cut it to form a beveled end, means for relatively moving the nozzle and knife into operative cutting position and into a retracted 75 position, and means for intermittently producing a vacuum within said hollow nozzle and for breaking said vacuum.

3. In a tube skiving machine, in combination, a rotating knife, an annular mandrel 80 coaxially disposed with relation to said rotating knife for supporting a tube end, the knife and the mandrel being relatively movable in such manner that the knife and the mandrel may be moved into operative cutting relation or retracted therefrom, means coordinated with the relative movements of the knife and the mandrel for holding the tube end firmly to the mandrel when in cutting position and for releasing the holding 85 action upon retraction therefrom.

4. In a tube skiving machine, in combination, a hollow nozzle externally tapered at one end and through which the end of a tube is adapted to be passed and to be folded back over the externally tapered portion, said hollow nozzle being provided with passage ways leading from the interior thereof to the outer wall of said tapered portion, a rotating knife adapted to circumscribe said folded-back portion of the tube and to cut it to form a beveled end, means for relatively moving the nozzle and knife into operative cutting position and into a retracted 95 position, and means coordinated with the relative movements of the knife and the nozzle for producing a vacuum within the nozzle when the two are in cutting position and for breaking the vacuum when the two are in retracted position.

100 5. In a tube skiving machine, in combination, a mandrel adapted for supporting a tube end and having a vacuum chamber therein, said mandrel being further provided with passageways to said chamber in a tube holding zone, a rotating knife adapted to cut said tube to form a beveled end thereon, means for relatively moving the mandrel and the knife into cutting position and into a retracted position, and means operative 105 upon relative movement of said knife and nozzle to cutting position for creating a subatmospheric pressure in said vacuum chamber and for releasing said pressure in retracted position.

110 6. In a tube skiving device, a hollow nozzle externally tapered at one end and through which the end of a tube is adapted to be passed and to be folded back over the externally tapered portion, a rotating tubu- 115 120 125 130

- lar knife adapted to circumscribe said nozzle into cutting position for holding the folded-back portion and to cut it to form folded-back tube end firmly to the nozzle. a beveled or skived end, means for relatively moving the nozzle and the knife into operative cutting position and into a retracted position, means operative upon said relative movement of the nozzle and knife into cutting position for holding the tube end firmly to the nozzle and for releasing the hold in the retracted position.
7. In a tube skiving device, a hollow nozzle externally tapered at one end and through which the end of a tube is adapted to be passed and to be folded back over the externally tapered portion, a tubular rotating knife adapted to circumscribe said folded-back portion and to cut it to form a beveled or skived end, means for moving the nozzle into operative cutting position with respect to the knife and for withdrawing the nozzle from the knife, and vacuum means operative upon moving the
8. In a tube skiving machine, in combination, a hollow nozzle externally tapered at one end and through which the end of a tube is adapted to be passed and to be folded back over the externally tapered portion, said nozzle being provided with passageways leading from the interior thereof to the outer wall of said tapered portion, a rotating knife adapted to circumscribe said folded-back portion of the tube and adapted to cut the extreme end portion of the tube with a beveled taper, means for relatively moving the nozzle and knife into operative cutting position and into a retracted position, and means for intermittently producing a vacuum within said hollow nozzle and for breaking said vacuum.

In witness whereof I have hereunto set my hand this 16th day of May, 1924.

ABRAM E. FALOR.
